CONVERTIBLE OTTOMAN AND BACK REST UNIT

Francis Torsak, Los Angeles, Calif.

Application April 27, 1953, Serial No. 24,676

Term of patent 14 years

(Cl. D15—1)

To all whom it may concern:

Be it known that I, Francis Torsak, a citizen of the United States, residing in Los Angles, in the county of Los Angeles and State of California, have invented a new, original, and ornamental Design for a Convertible Ottoman and Back Rest Unit, of which the following is a specification, reference being had to the accompanying drawing, forming part thereof.

Fig. 1 is a perspective view of a convertible ottoman and back rest unit, showing my new design.

Fig. 2 is a side view thereof, arranged as a back rest.

Fig. 3 is a similar view showing the ottoman in folded condition.

I claim:

The ornamental design for a convertible ottoman and back rest unit, substantially as shown.

FRANCIS TORSAK.
